UNITED STATES PATENT OFFICE.

DAVID FRANCIS CRAWFORD, OF PITTSBURGH, PENNSYLVANIA.

AUTOMATIC STOKER.

1,181,215.

Specification of Letters Patent.

Patented Mar. 9, 1915.

Application filed June 27, 1910. Serial No. 569,162.

To all whom it may concern:

Be it known that I, DAVID F. CRAWFORD, a citizen of the United States, residing at Pittsburgh, in the county of Allegheny and State of Pennsylvania, have invented certain new and useful Improvements in Automatic Stokers, of which the following is a specification.

The invention relates to automatic stokers, of the underfeed type, and has for its principal objects, the provision of an improved form of auxiliary feed construction which will effectively agitate and feed the fuel in the trough employed; and the provision of a trough and auxiliary feed construction which may be cheaply constructed, and conveniently assembled. Certain embodiments of the invention are illustrated in the accompanying drawings wherein—

20 Figure 1 is a plan view of the trough provided with my improved feed construction,

Figure 2 is a longitudinal section through the trough.

Figure 3 is a section on the line III—III 25 of Fig. 2 and,

Figure 4 is a perspective view of the end of a modified form of feed piston.

The drawings illustrate only the feed trough with the feeding pistons supplied thereto, but it will be understood that the trough is used in the usual way in a furnace, with grates extending along the sides and across the ends thereof. As shown in the drawings, 1 is the body of the feed trough, preferably a casting; 2 and 3 are closure plates for the slots at the bottom of the body portion 1 in which the auxiliary feed pistons reciprocate; 4 and 5 are the auxiliary feed pistons, which feed pistons, as indicated diagrammatically, are operated from an oscillatory shaft 6 by means of the crank arm 7 and the links 8, 9, 10 and 11; 12 is a main feed piston reciprocating in the cylinder 13 at the rear end of the trough; 45 and 14 indicates the lower edge of the water leg of the locomotive furnace to which the apparatus may be applied.

As indicated in Fig. 3, the auxiliary feed piston 5 is preferably rectangular in cross section, and is provided at its front end with the teeth 15, which teeth have been found to be a desirable addition, as they serve to break up and agitate the fuel more effec-

tively than a plain piston does. The piston 55 4 is similarly constructed, but in addition has its front end beveled at 16 in order to present a wedged shaped cutting surface, and also has its upper end surface beveled as indicated at 17. The beveling of these 60 surfaces enables the piston to cut through and agitate the fuel effectively without packing the fuel, as sometimes occurs with a square headed piston. The front piston 5 may be also beveled if so desired, but at 65 this point in the trough the square headed piston is probably more desirable in that a positive forward feed is desired at this point in order to force the fuel out at the end of the trough, while this is not so necessary 70 in case of the rear piston 4. The sheathing of the pistons 4 and 5, instead of allowing such pistons to lie wholly within the trough is desirable as with pistons so sheathed there is practically no tendency to carry the 75 coal backward on the rear movement of the piston which is not the case where the feed members lie wholly within the trough and are not sheathed. The feed pistons angular in cross section have been found to secure 80 a somewhat better feeding effect than the round pistons heretofore proposed for use as auxiliary feeding means.

The use of the removable closure plates 2 and 3 is desirable in that access is thus 85 given to the slots for any machine work necessary, the casting is more readily made than if the parts 2 and 3 were integral with the body portion 1, and the parts may be more conveniently assembled than if the 90 parts 2 and 3 were integral with the body portion 1. Other advantages incident to this construction will be apparent to those skilled in the art.

If desired the auxiliary pistons may be 95 made with plain rectangular shaped ends as indicated in Fig. 4, a member 18 bolted to the top serving in such case as the agitating means.

Having thus described my invention and 100 illustrated its use, what I claim as new and desire to secure by Letters Patent is the following:

1. The combination with a feed trough, 105 of an auxiliary feed piston mounted for reciprocation longitudinally of the trough through the bottom thereof and having ad-

2
jacent its front end an agitating projection upon its upper face.

2. The combination with a feed trough, of an auxiliary feed piston mounted for reciprocation longitudinally of the trough through the bottom thereof and having adjacent its front end a toothed upper face.

In testimony whereof I have hereunto signed my name in the presence of the two subscribed witnesses.

DAVID FRANCIS CRAWFORD.
